UNITED STATES PATENT OFFICE.

GEORGE A. ARNOLD, OF MIDDLETOWN, CONNECTICUT, ASSIGNOR TO ARNOLD ELECTRIC COMPANY, A CORPORATION OF MASSACHUSETTS.

VAPORIZER.

1,072,685.

Specification of Letters Patent.

Patented Sept. 9, 1913.

Application filed March 24, 1913. Serial No. 756,376.

To all whom it may concern:

Be it known that I, GEORGE A. ARNOLD, of Middletown, in the county of Middlesex and State of Connecticut, have invented 5 certain new and useful Improvements in Vaporizers, of which the following is a specification, reference being had to the accompanying drawings, forming part thereof.

10 This invention has reference to improvements in vaporizers and particularly to vaporizers adapted to supply heat to air or other fluid passing therethrough.

One object of the invention is to so construct a vaporizer having a series of heat radiating units that air or other fluid in its passage through the vaporizer shall be subjected to the most intense heat at or about the initial point of such passage and thereafter be caused to circulate about the heating units of less intensity.

Another object of the invention is to so construct a vaporizer of this nature that a series of heating units may be sustained by 25 members mounted for removal with a wall of the vaporizer chamber and positioned thereby relative to the vaporizer inlet.

Other objects of the invention will appear from the following description.

30 The invention consists in the novel construction and arrangement of the heat radiating units.

The invention also consists in such other 35 novel features of construction and combination of parts as shall hereinafter be more fully described and pointed out in the claims.

Figure 1, represents a longitudinal sectional view of the improved vaporizer as 40 taken on a line 1—1 Fig. 2. Fig. 2, represents an end view of the vaporizer. Fig. 3, represents a cross sectional view taken on line 3—3 Fig. 1 looking in the direction indicated by the arrows of said line.

45 Similar characters of reference designate corresponding parts throughout.

This improved vaporizer is particularly adapted to be attached to and form part of the air intake pipe or flue of a carburetor 50 for a combustion engine or to be applied as a conduit between the carburetor and the engine but, in its broad principle of application, this vaporizer may be utilized in any manner to supply heat to fluid passing therethrough.

In the simple embodiment of the invention of which the preferred form is shown in the drawings 5 indicates the wall of the vaporizer chamber which, preferably, is cylindrical in shape and is supplied with the 60 heat insulating lining 6, usually of asbestos. 7 and 8 are the head members of the vaporizer and are furnished with central openings which are defined by clamping collars 9 and 10 adapted to be clamped onto the 65 ends of pipe members by the tightening of their screws 11 and 12. The peripheries of said members 7 and 8 have respectively the lips 13 and 14 which embrace the wall of chamber 5 and have ears 15, 15 and 16, 16 70 through which extend screws 17, 17 and 18, 18 the inner ends of which are secured in perforations of the wall of chamber 5.

Mounted in diametrically positioned openings of the head 8 are the bushings 19, 19 of 75 hard rubber or of some other electrical insulation. Secured in place in the bores of said bushings are the terminals 20, 20 preferably of copper and of comparatively large size. These terminals are bent inward, toward 80 each other, and have the members 21, 21 which are approximately parallel. Provision is made for limiting the movement of said terminals 20, 20 through the bushings 85 19, 19 by reducing the end portions of the terminals to form the shoulders 22, 22 which bear against said bushings while the exterior end portions of said terminals are furnished with the wire-binding nuts 23, 23. Secured to the members 21, 21 of said terminals 20, 90 20 are the disk deflectors 24, 25 and 26 which preferably are circular in shape and of different size, the disk deflector 24 being preferably smaller than the deflectors 25 and 26. 95 These deflectors are of cast plaster or other suitable material adapted to resist heat and to form electric insulators whereby the heating coils carried by said deflectors are insulated electrically from the terminals 20, 20. Mounted on the peripheries of the deflectors 100 24, 25 and 26 are heating or electrical resistance coils 27, 28 and 29 which respectively are connected electrically, in parallel, with the terminals 20, 20. These coils 27, 28 and 29 are of German silver or other electrical 105 resistance material and the length of wire in said coils differs, the length of wire in coil 27 being less than that in coil 28 and that in turn being of less length than that of coil 29, so that the coils 27 and 28 are adapted to be 110

raised to a higher temperature than coil 29 by the same amount of electric current. The convolutions of the wire of coils 27 and 28 have the interposed asbestos or other heat resisting material 30 and 31 while the convolutions of coil 29 are open to permit the circulation therethrough of the fluid to be heated.

If it be understood that the terminals 20, 20 are supplied with a suitable electric current it is evident that the temperature of the coils 27, 28 and 29 will be raised because of their resistance to the passage of said current and fluid entering the vaporizer chamber through the opening of its head 8 will be deflected by the deflector 24 and will pass over and receive heat from its heating element or coil 27; the thus heated fluid will expand and enter between deflectors 24 and 25 and will again be directed toward the wall of the chamber and will pass over the coil 27 and receiving heat therefrom will expand more readily; a like operation occurring as the expanded fluid is again deflected by deflector 26 with the addition that the expanded fluid may circulate between and around the convolutions of the coil 29 which tends to maintain the temperature of the fluid and distribute the heat more evenly therethrough.

Having thus described my invention I claim as new and desire to secure by Letters Patent.

1. A vaporizer of the nature described comprising a cylindrical chamber, a pair of clamping collars having members removably mounted on said chamber and forming the ends thereof, a pair of electric conductors carried by a member of one of said collars.

Copies of this patent may be obtained for five cents each, by addressing the "Commissioner of Patents, Washington, D. C."

and forming supporting members within said chamber, a series of deflectors of electric insulating material mounted on said conductors, and a series of electric resistance coils carried by said deflectors, whereby said clamping collar, conductors and deflectors form a removable unit.

2. A vaporizer of the nature described comprising a cylindrical chamber, a head secured to said chamber, a pair of electric terminals extending through said head, a series of deflectors mounted on said terminals and increasing progressively in diameter, and electric resistance coils embracing said deflectors and in electrical connection with said terminals, one of said coils having its convolutions packed with heat resisting material and another of said coils being open for the circulation of fluid therebetween.

3. The combination with a cylindrical chamber, a head secured to such chamber and having an inlet opening and a clamping collar, a pair of electric terminals extending through said head, a deflector mounted on said terminals and in line with said inlet, an electrical heating coil of comparatively high intensity mounted on said deflector and electrically connected with said terminals, and a pair of deflectors spaced apart on said terminals at a distance from said first deflector and having electrical heating coils of progressively decreasing intensity in electric connection with said terminals substantially as described.

GEORGE A. ARNOLD.
